E. T. HAILS

ROLL TOWEL CABINET

Filed Sept. 29, 1924

UNITED STATES PATENT OFFICE.

EDWARD TROY HAILS, OF MONTGOMERY, ALABAMA.

ROLL-TOWEL CABINET.

Application filed September 29, 1924. Serial No. 740,512.

My invention relates to roll towel cabinets of the character in which a roll containing a clean towel is adapted to be introduced into the cabinet which comprises mechanism for automatically feeding and rewinding the towel as it becomes soiled on a soiled towel roll which, when filled, can be removed from the machine and the operation repeated. In cabinets of this character the chief objects that must be attained to render the device commercially successful are:

1st: The manner of operating the cabinet by the public must be simple and obvious.
15 2nd: The public must be prevented from drawing off more than the prescribed allotment of towel for each service.
3rd: The service loop shall be concealed so as to make the cabinet as attractive and 20 pleasing in appearance as possible; and
4th: All of the movements incidental to the unwinding and rewinding of the towel shall respond automatically to the opening and closing of that part or door of the cabinet which, when closed, conceals the service loop.

To these ends my invention contemplates the provision of a cabinet adapted to receive clean and soiled towel rolls and having associated with each of said rolls a friction feed roll, the latter rolls being connected for alternate operation responsive to the opening and closing of the selective movable part of the cabinet which normally conceals the service loop. In my preferred construction this movable part of the cabinet is the bottom of the cabinet and the opening of it will unwind sufficient clean towels to furnish the standard size service loop, and the closing of it will rewind the soiled towel into the cabinet.

My invention further contemplates the provision of simple and effective means which are positive in their action and which 45 prevent a pull on the service loop, unwinding the towel from the clean or soiled towel rolls.

My invention further comprises the novel details of construction and arrangements of parts, which in their preferred embodiment only are illustrated in the accompanying drawings which form a part of this specification, and in which:

Fig. 1 is a side view of my improved cabinet with the near end wall removed and

with the bottom door shown in dotted lines in its open position.

Fig. 2 is a front view of the cabinet showing part of the front broken away on the line 2—2 of Fig. 1 to expose the internal operating mechanism.

Fig. 3 is an enlarged detail view of the clean towel roll latch in its operating position.

Fig. 4 is a detail view of the clutch drive connection between the sprocket and roller.

Similar reference numerals refer to similar parts throughout the drawings.

As illustrated, I show a cabinet having a top 1, a front 2 with an opening enclosed by a hinged door 3, a back wall 4, and end walls 5 and 6. To the bottom of the back wall 4 I hinge a bottom closure 7 for the cabinet, which closure is deeply recessed so as to provide a pocket to receive the shortened service loop of the towel which will be later described. This bottom closure is provided with any suitable latch means 8 by which it is normally held in its raised or closed position in which it contacts with the sides and front of the cabinet and forms an effective closure which conceals the service loop of the towel. A horizontal partition 9 extends across the bottom, stopping short of the front and back walls. This partition, adjacent to the end wall 6, is provided with a slot 10 through which passes the towel operating arm 11 which is pivotally connected at 12 to the inside of the bottom closure 7. This arm 11 at its upper end is twisted and suitably connected by a pin 13 to a sprocket chain 14 passing over clutch sprockets 15 and 16 which are mounted on the axes 17 and 18 respectively of the upper friction feed roll 19 for the dirty towel, and the lower friction feed roll 20 for the clean towel. These clutch sprockets are provided with internal cam surfaces 21^a engaged by rollers 21 which bear on the shaft 17 or 18, and it will be seen by the disposition of the cam surfaces that the sprocket 15 will clutch the shaft 17 only when it is moved counter-clockwise and that the clutch sprocket 16 will only engage the shaft 18 when moved clockwise.

It follows that the sprocket 15 will move idly in a clockwise direction and that the sprocket 16 will move idly in a counter-clockwise direction. As the bottom closure 7 is swung downwardly the clutch sprocket 16 acts to drive the feed roll 20, while on the reverse

movement the clutch sprocket 15 operates to drive the feed roll 19. 22 is a roll carrying the clean towel 23 while 24 is a rewind roll to receive the soiled towel. The bottom 5 partition 9 is spaced sufficiently from the front and back walls of the box to permit the towel to pass from the clean towel roll through the service loop compartment in the closure 7 and back upwardly over a guide 25 10 to the rewind roll 24. A pivoted clamp bar 26 is disposed in the rear of the cabinet and provided with a sand-papered or roughened edge 27 which is adapted to be pressed by gravity against the towel and to serve as a 15 clamp to prevent the soiled towel being pulled downwardly and unwound from the roll 24.

To prevent the unwinding of the towel from the clean towel roll 22, I provide on the 20 end of the friction feed roll 20 a series of pins 28 and I pivotally mount on the operating bar 11 a hook latch 29 normally held by a spring 30 in position in which, when the closure 7 is in fully opened position, this 25 hook will engage or move into the path of one of the pins 28 and will prevent the rotation of the friction feed roll 20 and thus the unwinding of the towel from the roll 22. The clean towel roll is removably mounted 30 in guides 31 formed in the end walls 5 and 6, the lower part of the guide being vertical so that the full weight of the clean towel will rest upon its feed roll 20. The soiled towel roll 24 is mounted in inclined guides 32 35 formed in the upper portions of walls 5 and 6. The feed roller shafts 17 and 18 are journaled in the end walls 5 and 6 and suitable bearings and a handle 33 can be provided for the cabinet closure 7.

40 In operation, the clean towel is introduced on its roll 22 and its free end is passed forwardly between the roll and the feed roller 20 and then downwardly past the front edge of the partition 9 and under the latter and 45 upwardly past the back edge or partition 9 and past the friction grip 26 and over the guide 25 and is passed forwardly about the rewind roll 24 and connected thereto. When ready for use the towel will have what I 50 term a preliminary or short service loop hanging down in the compartment provided therefor in the closure 7. Ordinarily this preliminary loop will hang in the compartment to a depth of about 4" from the center 55 of the partition 9 and this will give about one-half of the amount of towel required for a full service loop. When the operator uses the cabinet he grasps the handle 33 on the bottom closure 7 and pulls it down to its 60 dotted position, Fig. 1. This acts through the operating bar 11 to pull the chain 14 in one direction, causing the rotation only of the feed roller 20 for the clean towel and it will rotate this roller sufficiently to feed 65 enough clean towel to approximately double

the amount of towel in the loop, thus giving what I call a full service loop which requires roughly about 18" of towel. When the towel has been used the operator is supposed to close the closure 7 and in doing so the 70 bar 11 will move the chain in the reverse direction, causing the operation of only the feed roll 19, which will take up on the soiled towel roll the amount of towel that was delivered by the operation of the opening of 75 the closure 7 to the service loop, thus withdrawing towel from the service loop so as to contract it to its small size. When the closure 7 is next opened the feeding of the 80 clean toweling which results will leave only 85 the latter exposed, leaving the soiled towel unseen in the loop at the rear thereof. When the door is fully opened the latch 29 will engage one of the pins 28 and prevent the movement of the friction roll 20 and thus 90 prevent any clean toweling being withdrawn by a pull exerted on the service loop. In the same manner the friction grip element 26 will prevent the unwinding of soiled toweling from the roll 24 and in this manner the 95 amount of toweling in the service loop is maintained substantially constant.

Though I have described with great particularity the details of the embodiment of the invention herein shown, it is not to be 95 construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a roll towel cabinet, a clean towel roll and a feed roll associated therewith, a soiled towel roll and a feed roll associated therewith, a common operating mechanism for said feed rolls adapted when moved in one direction to rotate only one roll and when moved in the reverse direction to rotate only the other roll, a movable closure on the cabinet adapted when operated to expose the service loop of the towel, and means operated responsive to the movement of said closure to unwind the clean towel into the service loop as the closure is opened and to rewind the soiled towel from the service loop onto the soiled towel roll as the closure is closed.

2. A roll towel cabinet according to claim 1, in combination with means to prevent the unwinding of the towel from either the clean or soiled towel rolls when the service loop is exposed.

3. In a roll towel cabinet comprising clean and soiled towel rolls and respective feed rolls therefor, of a common operating mechanism which when moved in one direction will operate one feed roll only and when moved in the reverse direction will operate

only the other feed roll, a bottom door for concealing the service loop of the towel, and means responsive to the opening and closing movements of said door to operate the actuating mechanism for said feed rollers.

4. A roll towel cabinet having a pair of friction feed rolls and means to mount clean and soiled towel rolls in position, each to coact with its respective feed roll, means to permit a service loop of towel to hang in the lower part of the cabinet, a movable door in the cabinet adapted when closed to conceal the service loop and when opened to expose it for use, mechanism responsive to the opening and closing of said door to change the towel forming the loop, the towel changing means comprising mechanism to feed clean towel into and increase the size of the service loop responsive to the opening of the door, and means to withdraw the added towel from

the loop and rewind it on the soiled towel roll responsive to the closing of the door.

5. A roll towel cabinet comprising a pair of feed rolls, a common clutch controlled drive for said rolls, a cabinet door adapted to operate said drive to rotate one roll as the door opens and the other roll as the door closes, clean and soiled towel rolls adapted to coact with their respective feed rolls, and a latch means movable with the door and adapted to prevent rotation of the clean towel feed roll when said door is fully opened.

6. A roll towel cabinet in accordance with claim 5, in combination with friction grip means to prevent the unwinding of the towel from the soiled towel roll responsive to a pull on the service loop.

In testimony whereof I affix my signature.
EDWARD TROY HAILS.
